UNITED STATES PATENT OFFICE.

HUGH WILLIAM McEWEN, OF CHICAGO, ILLINOIS.

SOAP CUTTING AND PRESSING MACHINE.

No. 852,190.

Specification of Letters Patent.

Patented April 30, 1907.

Application filed August 14, 1906. Serial No. 330,526.

To all whom it may concern:

Be it known that I, HUGH WILLIAM McEWEN, a citizen of the United States, and a resident of Chicago, in the county of Cook and State of Illinois, have invented a new and Improved Soap Cutting and Pressing Machine, of which the following is a full, clear, and exact description.

This invention comprises a new and improved machine for cutting long bars of soap into short sections and pressing each of said sections into a regular sized cake.

The object thereof is to produce a device of this character which is automatic in its operation and which carries on all the necessary steps in their regular sequence without the aid or attention of a skilled operator.

The invention further consists in the combination of elements hereinafter set forth, whereby the desired results are accomplished.

Reference is to be had to the accompanying drawings forming a part of this specification, in which similar characters of reference indicate corresponding parts in all the figures, in which

Figure 1 is a side elevation of the complete machine; Fig. 2 is a vertical longitudinal section; Fig. 3 is an end elevation showing certain of the parts in section; Fig. 4 is a plan view of the receiving pockets and mechanism for spacing the same; Fig. 5 is a detailed plan view of the means employed for releasing the upper portion of the mold; and Fig. 6 is a detailed section showing a portion of the mold and its releasing means.

In my invention I preferably employ a main rectangular frame having side bars 1 and suitable supporting legs 2. Journaled in suitable bearings at one end of this frame, is the drive shaft 3 by which the working parts are operated. This drive shaft carries a suitable fly wheel 4 on one end and two cranks intermediate its ends. The cranks 5 have connecting rods 6 pivoted to the ends thereof and connected to the working parts of the machine. At the opposite end of the machine are two standards 7, having a platform 8 extending across the machine and serving as a support for the bars of soap before the same are fed into the cutting mechanism. The platform 8 has a slot extending substantially the entire length thereof and of sufficient width to permit of the passage 55 of the soap bar. This slot is sub-divided by a plurality of wires 9 extending from one

side of the platform to the other and of a sufficient distance apart so that the small cakes of soap formed thereby will be of the proper proportions. Supported above 60 this slot is a plunger 10 of slightly less width than the slot in the platform and having grooves 11 cut upward to permit of the passage of the plunger into said slot and the insertion of the wires in the said grooves. 65

The soap to be cut up and formed into cakes is usually supplied in the form of long cylindrical bars which are placed on the platform 8 and as the plunger 10 is raised the bar of soap is placed over the slot and supported on the cross wires 9. As the plunger 10 descends, it forces the bar of soap down through the slot and the wires serve to cut the bar into a plurality of small sections, while the wires pass upward into the grooves 75 in the plunger and permit a free up and down movement thereof. For reciprocating the plunger, I extend the ends thereof beyond the standards 7 and mount said ends upon vertical rods 12 adapted to be reciprocated in any suitable manner but preferably by the mechanism about to be described. The upper end of the rods 12 extend through the upper side of the frame and have coiled springs 13 mounted thereon and tending to 80 lift the rods and therefore the plunger against the action of gravity.

Within the main rectangular frame are mounted two wedge-shaped plates 14 adapted to be moved longitudinally of said frame 90 by the rotation of the main drive shaft 3. These wedge-shaped plates 14 fit in grooves on the under side of the frame and have their cam surfaces on the lower side. The rods 12 extend down below the lower edge of these 95 plates and are provided with suitable anti-friction rollers 15 adapted to bear against the under side of the two wedge-shaped plates. As the two plates are moved toward the right-hand side, it will be noted that the anti-friction rollers are traveling along the under side of the plates and being raised together with the plunger by the action of the coiled springs 13; but when the triangular plates 14 are moved in the opposite direction, namely, 100 from the right to the left, the anti-friction rollers 15 are drawn down, and thus by springing upon the plunger 10, cause it to pass through the slot in the platform 8, and sub-divide a bar of soap supported on the 110 cutting wires 9. The under side of the plunger 10 is preferably concave to fit the soap

bar, and suitable guides may be employed, if desired, to prevent the bar of soap from sliding off the further side when it is placed upon the cutting wires.

5 For receiving the shorter bars of soap as they fall from beneath the cutting wires 9, I provide a plurality of open-ended pockets 16, supported upon two cross bars 17 along which they are adapted to slide. These 10 pockets 16 are provided with lugs 18 for properly spacing them apart, and are provided with chains or other suitable connecting means 19 to prevent the pockets from being moved more than a predetermined distance apart. For moving the pockets apart 15 after the cakes of soap have fallen therein, I provide one of the pockets with a bar 20 extending out through one of the standards 7, and having means on the outer end thereof 20 for reciprocating said rod at the desired time in the operation of the machine. The bottom 21 of each of the pockets is hinged to the side wall and normally held closed by a suitable spring 22, while the opposite edge of the 25 bottom is extended to form a catch 23 adapted to engage with the mold and open the bottom of the pocket to discharge the contents into the mold as the latter reaches the required position.

30 Extending across the main frame of the machine intermediate its length, is a heavy cross beam 24 carrying a portion of the soap mold and having the triangular plates 14, previously referred to, rigidly attached thereto. 35 This cross beam also carries a second set of substantially triangular plates 25 extending longitudinally of the machine and in an opposite direction from the plates 14, and by which motion is transmitted from the connecting rod 6 to the cross beam 24, as these plates 25 are adapted to be reciprocated along the frame by said connecting rod which may be secured to the latter in any suitable manner.

40 The second or reciprocating portion 26 of the mold comprises a heavy weight extending across the frame and having recesses or cavities 27 in the lower side thereof, into which the soap fits as the mold is operated in 45 the manner hereinafter described. This weight 26 has two rods 28 extending outward therefrom and in alignment therewith, both of which are connected to sleeves 29 supported to reciprocate the stationary rods 30. 50 Each rod 28 is also provided with anti-friction rollers 31 adapted to rest on the upper surface of each of the cam plates 25, whereby as the said plates are moved longitudinally of the frame, the weight 26 will be raised or 55 lowered according to the direction of the movement of said plates. Connecting the upper ends of the two stationary rods 30 is a cross piece 32 having a vertical passage through which extends a rod 33 carried by 60 the weight 26 on the upper surface thereof.

This rod 33 has a notch 34 cut in one side of the same and the upper side of the cross piece 32 has a spring-pressed lever 35 pivoted thereto and adapted to engage the notch 34 in the rod 33 when the weight is raised a sufficient distance by the longitudinal movement of the triangular plates 25. For releasing the lever 35 from the notch 34, I connect the opposite end of said lever by a rod 36 to a suitable trigger 37 lying in the line of movement of the triangular plates 25 or their supporting member. This trigger is preferably mounted in a suitable guide 38 and normally held in one position by a suitable spring 39. To one end of the trigger 37 is secured the rod 36, and the trigger is so located that it does not contact with the plate or its supporting member until the plate 25 has very nearly reached the limit of its movement, at which time the beam 24, constituting the lower portion of the mold, is directly below the weight 26 and the latter is allowed to drop.

The lower portion of the mold is mounted to move along the frame together with the triangular plates 14 and 25, but as it is essential that the said mold should be in exactly a certain given position at the time the upper portion of the mold is released and dropped, the lower portion preferably has a certain freedom of motion in the frame and is normally held to its extreme left-hand position by a suitable spring 40. As the triangular plates and cross beam 24, constituting the lower portion of the mold, are moved toward the left-hand, the cross beam 24 contacts with a stop 41 of any suitable character and the plates 25 and 14 may continue their movement until the trigger 37 is operated and the upper half of the mold allowed to drop upon the lower half. For suitably supporting the cross beam at the time the weight is dropped, I preferably provide suitable standards or supports 42 of any suitable character, with the upper surfaces of which the mold comes in contact, whereby the shock caused by the dropping of the upper portion of the mold is received on said standards instead of upon the main frame of the machine.

115 The cross beam 24 has recesses cut therein and adapted to receive the mold blocks 43, which may be raised up out of the cross beam 24 and permit of the discharge of the completed cake of soap in the following manner: 120 Each mold block 43 has a rod or bar 44 extending downward therefrom and adapted to be capable of a short reciprocating motion. Hinged to the lower end of each of the rods 44 is a second member 45 having an anti-friction roller 45^a on its lower end, adapted to engage with triangular plates or cam surfaces 46, whereby as the cross beam 24 is moved toward the right the anti-friction 125 rollers engage the cam surfaces of the plates 130

46 and raise the mold blocks 43 out of the cross beam. As the motion of the cross beam progresses, the finished cakes of soap may come into engagement with down-hanging 5 baffles 47 supported on a rod 48, or in any other suitable manner, and the finished cakes thus brushed or pushed from the mold blocks 43 and allowed to fall beneath the frame.

10 After the finished cakes are removed as above described, the mold continues onward toward the right until the edge of the mold contacts with the extension 23 on the bottom of the corresponding pocket. This tends to 15 open the pocket in opposition to the action of the spring 22 and at the time the mold reaches the end of its course, the bottom of the pocket is opened sufficiently wide for the cake of soap to escape into the mold. As the 20 rod 44 has its extension 45 hinged thereto, it is evident that the mold may freely return to its normal position without the cake being rejected from the mold. The baffles 47 are 25 free to swing toward the left to permit of this return but are prevented from swinging toward the right, whereby the cake is positively removed from the forward movement of the mold.

As the recesses in the mold must of necessity be a certain distance apart, and as there is no appreciable distance between the ends of the respective cakes as they fall from the cutting wires 9, it is desirable that the receiving 30 pockets may space apart after they receive the cakes of soap from the cutting wires and before they deliver the same to the molds. To accomplish this, the pockets are connected by chains 19, as previously described, and the bar 20 connected to the end 35 pocket extends out through one of the standards 7 and is provided with a coiled spring 49, normally tending to force the pockets together. The end of this rod is provided with a vertical tee having small anti-friction rollers 50 on the two ends thereof and adapted to rest on the outer cam surfaces of two parallel triangular plates 51, adapted to move back and forth across the standard 7. For moving these plates, I provide them 40 with an extension 52, having a coiled spring 53 normally tending to force them in one direction, while an arm 54 is pivoted to the upper portion of the frame and rests against a roller 55 on the opposite end of the plates. The arm 54 extends downward to the main frame and is adapted to be engaged by the end of a U-shaped stop 56 carried by the cross beam 24 and curved so that it does not interfere with the free motion of said beam 45 to a position beneath the pockets. As the beam 24 carrying the molds is moved toward the right, it contacts with the end of the lever 54, and in moving the latter it forces the plates 51 beneath the rollers 50 and thus draws out the rod 20 against the action of

the spring 49 and pulls the pockets a sufficient distance apart, whereby each pocket will be directly above its corresponding mold.

The reciprocating parts of the machine 50 may be separated within the main frame and may be secured to the connecting rods 6 in any suitable manner. Preferably the end of the cross beam 24, having the lower portion of the mold, is provided with recesses in the 55 ends thereof adapted to receive the side members 1 of the main frame and a second cross beam 57 is similarly supported, as indicated in Fig. 6, with the plates 25 secured to the upper side thereof and the two connect- 60 ing rods journaled intermediate its ends.

In the operation of my improved soap cutting and pressing machine, the shaft 3 is rotated from any suitable source of power and long cylindrical bars of soap are placed on 65 the platform 8. Starting with the parts in their extreme left-hand position, the plunger 10 will be at its lowest position and the weight 26, constituting the upper half of the mold, will rest upon the lower half with the 70 finished cakes of soap between the two. As the machine is started, the triangular plates 25 move toward the right and raise the weight 26 off the cross beam 24 before the latter begins to move as the cross beam is in 75 such a position on the frame that the spring 40 was slightly compressed at the time the weight fell. After the weight has been raised a short distance above the cross beam 24, the latter begins its movement toward 80 the right and as the extension 45 comes in contact with the beveled surfaces of the plates 46, the cakes are raised from the recesses in the beam 24 and upon further movement they are brushed off by the plates 85 47. As soon as the extension 45 passes the end of the plates 46, the lower portions of the molds drop within the recesses of the cross beam 24 and the latter then engages with the bottom of the pockets 16 and permits the 90 discharge of the unfinished cakes from said pockets into the recesses in the beam 24. Meanwhile, the stop 56 has engaged the lever arm 54 and spaced the pockets apart and the roller 15 has passed up the cam surface 95 of the plate 14 to raise the plunger 10 for the insertion of a new bar of soap from the platform 8. As the parts move toward the left, the plunger is brought down and the pockets allowed to come together by the disengagement of the stop 56 from the lever arm 54. The beam 24 can freely pass beneath the baffles 47 and then pass over the standards 100 51 until it engages with the stop 41. During this return movement, the weight 26 has been held at its highest position by the engagement of the catch 35 with the notch 34, and as the cross beam reaches a position directly beneath the weight 26, the other parts 105 of the machine may move still further, due 110

to the action of the spring 44 and upon this further movement the trigger 37 is pulled and the catch 35 released from the notch to permit the weight to instantly descend upon the unfinished cakes of soap resting in the recesses in the cross beam 24 and thus compress them into the desired shape. The walls of these recesses may be provided with any suitable lettering or design which it is desired to stamp upon the finished cakes of soap at the time they are thus formed. By the time the weight drops the plunger 10 has been again drawn down by the action of the plates 14 and the next bar of soap has been cut into sections by the wires 19 and deposited into the receiving pockets below.

It is of course understood that my machine is not limited to the forming of cakes from bars of soap, as it is evident that the machine may be used with any plastic or semi-plastic substance which it is desired to treat in the same way.

Various changes may be made in the construction of the machine above described, and it is evident that various of the parts may be replaced by their equivalents or used by themselves in different relations without departing from the spirit of my invention.

Having thus described my invention, I claim as new and desire to secure by Letters Patent:

1. In a soap cutting and pressing machine in combination, means for sub-dividing a bar into a plurality of cakes, pockets to receive each of said cakes, means for moving said pockets to space the same apart, and means adapted to receive the cakes from the pockets and press them to the desired shape.

2. In combination, a platform having a slot therein, a plurality of wires extending across said slot, a plunger mounted above said platform and adapted to pass through the slot therein, vertical rods upon which said plunger is mounted, and longitudinally moving plates having cam surfaces adapted to engage the lower end of said rods and depress the same, and causing the plunger to pass through the said slot.

3. In combination, two vertical standards, a platform mounted on the said standards, a vertical reciprocating rod adjacent each of said standards, a spring on each of said rods normally tending to raise the same, a plunger carried by said rods and adapted to pass through an opening in the platform, and plates movable in respect to the platform and having cam surfaces adapted to engage with said vertical rods, whereby upon the longitudinal movement of said plates, the plunger is forced through the opening in the platform.

4. In combination, means for sub-dividing a bar of plastic material into a plurality of sections, pockets adapted to receive said sections, a plurality of molds in which said sec-

tions are pressed, and means for moving said molds toward said pockets and simultaneously spacing said pockets apart.

5. In combination, means for sub-dividing a bar of plastic material into a plurality of sections, a plurality of open-ended pockets beneath said sub-dividing mechanism and adapted to receive the said sections, means for moving said pockets longitudinally to space the sections a greater distance, and means for opening the lower side of each of said pockets to permit the escape of the contents thereof.

6. In combination, means for sub-dividing a bar of plastic material into a plurality of sections, a plurality of longitudinally movable pockets mounted beneath said sub-dividing mechanism and adapted to receive said sections, means connecting each of said pockets to the next succeeding one to limit the distance to which they may be separated, and means for moving one of said pockets longitudinally.

7. In combination, a plurality of mold sections, corresponding mold sections mounted above the same and adapted to be brought in contact with said first mentioned mold sections, means for moving said first mentioned mold sections laterally and simultaneously raising the bottom thereof, and a baffle adapted to engage with the contents of the molds to remove the same upon further lateral movement of the mold sections.

8. In combination, a laterally movable base mold section, a reciprocating mold section adapted to be brought into engagement therewith, means for raising the bottom of said mold section as the latter is moved laterally, means for removing the contents of said mold section upon further lateral movement thereof, and means for refilling said mold section upon still further lateral movement.

9. In combination, a laterally movable mold section, means for removing the contents thereof upon the lateral movement of said section, a pocket, means for moving said pockets into alignment with the mold sections, and means for discharging the contents of said pocket into said mold section upon the further lateral movement of the latter.

10. In combination, a laterally movable mold section, means for filling the said section, supports over which said section is adapted to be moved, a vertical reciprocating mold section adapted to be brought in contact with said base section, and means for releasing said vertically movable section and permitting it to drop upon the base section as the latter reaches a position above said supports.

11. In combination, a rectangular frame, standards mounted upon the said frame, a vertically movable mold section slidable on the said standards, two plates mounted to

- move longitudinally of said frame, the upper edge of each of said plates being inclined, means whereby the mold section will be raised upon the longitudinal movement of said plates, means for holding said mold section in its raised position during the return movement of said plates, and means for releasing said mold section upon the completion of said return movement.
10. 12. In combination, a frame, an upper mold section movable only in a vertical plane, a lower mold section movable only in a lateral plane, and means for simultaneously raising said upper mold section and laterally moving said lower mold section.
15. 13. In combination, a frame, sub-dividing means mounted thereon, receiving pockets, a vertically movable mold section, a laterally movable mold section, and means for simultaneously raising said vertically movable mold section, removing the contents of said laterally movable mold section and raising said sub-dividing means.
20. 14. In combination, a plurality of pockets, a plurality of mold sections, and means whereby upon the lateral movement of said sections the contents of said molds is removed and the contents of said pockets delivered to said molds.
25. 15. In combination, a plurality of pockets, means for sub-dividing a bar of plastic material and delivering a section to each of said pockets, chains connecting said pockets, molds adapted to be moved beneath said pockets, and means whereby the chains are drawn taut and the pockets placed to the maximum distance simultaneously with the movement of the mold sections beneath said pockets.
16. In combination, a plurality of pockets, means for supporting said pockets, a bar secured to one of said pockets, a plate having an inclined edge adapted to be moved in contact with said bar and move the same longitudinally, a spring normally tending to move said bar in the opposite direction, flexible means connecting said pockets, and means for moving said plate in contact with said bar, whereby the latter is moved longitudinally and the pockets spaced to a greater distance apart.

In testimony whereof I have signed my name to this specification in the presence of two subscribing witnesses.

HUGH WILLIAM McEWEN.
